[57] **CLAIM**

The ornamental design for a combined door knob and escutcheon, as shown.

DESCRIPTION

FIG. 1 is a perspective view showing the front, right side and bottom of a combined door knob and escutcheon showing my new design;

FIG. 2 is a right side view thereof, the left side being a mirror image of the right side;

FIG. 3 is a front view thereof; the back, being devoid of ornamentation, is not shown;

FIG. 4 is a bottom view thereof; and

FIG. 5 is a top view thereof.
